United States Patent Office

Des. 211,474
Patented June 18, 1968

211,474

MAGNETIC TAPE RECORDER

Norman R. Kubnick, Skokie, Ill., assignor to Bell & Howell Company, Chicago, Ill., a corporation of Illinois

Filed Sept. 12, 1967, Ser. No. 8,565

Term of patent 14 years

(Cl. D26—14)

Fig. 1.

Fig. 2.

Fig. 3.

FIG. 3 is a perspective view similar to FIG. 1 with the recorder placed in an alternate position; and

The ornamental design for a magnetic tape recorder, as shown.
